(57) **CLAIM**

The ornamental design for a magnifier camera, as shown and described.

DESCRIPTION

FIG. 1 is a right side perspective view of a magnifier camera in the deployed configuration.

FIG. 2 is a left side perspective view of the magnifier camera in the deployed configuration.

FIG. 3 is a front elevational view of the magnifier camera in the deployed configuration.

FIG. 4 is a rear elevational view of the magnifier camera in the deployed configuration.

FIG. 5 is a left side elevational view of the magnifier camera in the deployed configuration.

FIG. 6 is a right side elevational view of the magnifier camera in the deployed configuration.

FIG. 7 is a top plan view of the magnifier camera in the deployed configuration.

FIG. 8 is a bottom plan view of the magnifier camera in the deployed configuration.

FIG. 9 is a top perspective view of the magnifier camera in the collapsed configuration; and,

FIG. 10 is a bottom perspective view of the magnifier camera in the collapsed configuration.
